UNITED STATES PATENT OFFICE

2,445,308

TUCK END SUPPORT

Clifford F. Randolph, Brooklyn, N. Y., assignor
to International Cigar Machinery Company, a
corporation of New Jersey

Application September 15, 1943, Serial No. 502,419

1 Claim. (Cl. 131—30)

1

This invention relates to cigar machines, more particularly to improvements in the wrapper-applying mechanism thereof. Heretofore the tuck end of the cigar in the wrapper-applying mechanism was supported by a nest of rollers, as shown in the patent to J. P. Durning, No. 2,290,171, while the bunch was revolved during the application of the wrapper to the bunch. Accordingly, a different nest of rollers had to be supplied for every variation in the diameter or shape of the tuck end of the cigar bunch.

It is an object of the present invention to provide instead of the said nest of rollers, a cup conforming to the shape of and supporting the tapered tuck end of the cigar bunch. Adjustment of said cup is also provided to accommodate tuck ends of greater or lesser diameter and the same or substantially the same general shape. Said cup may also be adjusted to compensate for wearing thereof which, surprisingly, may be sufficient to affect the position of the cigar bunch relative to the rolls which apply the wrapper thereto.

With this and other objects not specifically mentioned in view, the invention consists in certain constructions and combinations which will be hereinafter described and then specifically set forth in the appended claim.

In the accompanying drawings, which form a part of this specification and in which like characters of reference indicate the same or like parts:

Fig. 1 is a fragmentary perspective view of the wrapper-applying mechanism of a cigar machine equipped with the cup of my invention instead of a nest of rollers; and

Fig. 2 is a detail sectional view of the bracket in which the cup is supported, showing the manner in which the stem of the cup is secured therein to permit vertical adjustment of the cup.

Referring to Fig. 1, wherein the invention is shown associated with a wrapping machine of the type described in the patent to J. P. Durning, No. 2,290,171, issued July 21, 1942, the top rollers 10 and 12 are supported at their ends in brackets 14, 18 and 16, 20, respectively. Brackets 14 and 18 are connected by a tie rod 22, and brackets 16 and 20 are connected by a tie rod 24.

Brackets 14 and 18 are pivotally mounted on the shaft 26 of one of the side rollers 28, and the brackets 16 and 20 are pivotally mounted on the shaft 30 of the other side roller 32. The shaft 26 of the roller 28 is supported at one end by a bracket 34 and at the other end by a bracket (not shown), both of these brackets being con-

nected by a tie rod 36 and pivotally mounted on a shaft 38 supported from a housing (not shown). The ends of the shaft 30 of roller 32 are supported by a bracket 40 also pivoted on shaft 38 and connected by a tie rod 42 to a similar bracket 44 partially shown in Fig. 1 and pivoted on shaft 38.

Brackets 40 and 34 are connected by links (not shown), corresponding to the links 39a and 39d shown in Fig. 1a of the above mentioned Durning patent, to arms (not shown), corresponding to the arms 67b and 67c of said patent, which are connected to a lever (not shown), corresponding to lever 61a of said patent and operated by a cam lever (not shown) corresponding to the lever 67f thereof, to open the rollers 28 and 32 to admit the cigar bunch which is to be wrapped and then move them into positions wherein they support the bunch.

On the tie rod 24 is secured a finger 50 which is urged upwardly by a compression spring 52 seated against a block 54 fastened on tie rod 42, to maintain the roller 12 in a position wherein it engages the top of the inserted cigar bunch. Tie rod 22 is provided with a finger 56, which engages a compression spring (not shown) seated on a block (not shown) fastened on tie rod 36, to maintain roller 10 in a similar position.

The header block 60 is supported from the housing (not shown), in the same manner as header block B in Fig. 2 of the Durning patent and serves to support the head end of the inserted cigar. The bunch positioner is similar to that shown in the Durning patent and consists of a bent arm 62 fastened on one end of the shaft 64 supported in a bracket 66 secured on shaft 38, the other end of shaft 64 being provided with an arm 68 carrying a pin 70 engaging a groove in the head 71 of a rod 72. The latter is operated by a link (not shown), corresponding to link 63 of the Durning patent (Fig. 7) and actuated by a cam lever corresponding to the lever 65 thereof.

On bracket 66 is mounted a cup 76 which is adapted to support the tuck end of the cigar bunch. Cup 76 is provided with a stem 78 which is inserted in a vertical hole 80 of bracket 66 and secured therein by a set screw 82 engaging a key 84 mounted in a vertical slot formed in a predetermined position in one side of hole 80 and engaging a key way in the stem 78 which is properly located to maintain cup 76 in a position aligned with the cigar bunch. The key 84 has a sliding fit in the keyway in stem 78 to permit the cup 76 to be adjusted vertically when set screw 82 is loosened. The bracket 66 is split and its split

énds are connected by a screw 86. Thus, upon unloosening screw 86, the bracket 66 may be slid along shaft 38 to position the cup 76 for various lengths of cigar bunches.

The shape of the cup conforms to the tapered tuck end of the cigar bunch which it supports. Thus upon adjusting the cup vertically, after unloosening set screw 82, the cup may accommodate greater or lesser diameters of tapered tuck ends of the same or substantially the same general shape.

What is claimed is:

In a cigar machine provided with rollers coacting to revolve a cigar bunch about which a wrapper is to be wound spirally, and a header block adapted to support the head end of said cigar bunch; a cup adapted to engage and support the lower sides of the tuck ends of cigar bunches of the same general shape but varying diameters, said cup having a generally horizontal elongated trough-shaped cavity of semi-circular cross-section open at each end and tapering longitudinally in general conformity to the taper of the tuck end of the cigar bunch supported thereon, supporting means for said cup arranged directly below the longitudinal axis of said cup whereby the cup may be shifted vertically and longitudinally to position the head end of said

cigar bunch in a predetermined position on said header block, said cup supporting means including a stem projecting downwardly from the cup, a support provided with a hole to receive said stem, and a device adapted to clamp the stem in said support to prevent undesired vertical movement of said cup, and permit vertical adjustment of said cup, whereby through vertical and longitudinal adjustment of said cup cigar bunches of different diameters and lengths may be supported on said cup in a predetermined position.

CLIFFORD F. RANDOLPH.
